GOLF CLUB HEAD

Guy N. Wetzel, Columbus, Ohio

Application June 28, 1955, Serial No. 36,741

Term of patent 7 years

(Cl. D34—5)

FIG. 1.

FIG. 2.

FIG. 3.

FIG. 4.

Fig. 1 is a perspective view of a golf club head showing my new design;

Fig. 2 is an end elevational view;

Fig. 3 is an elevational view looking toward the side of the golf club head opposite that shown in Fig. 1; and

Fig. 4 is a bottom plan view.

I claim:

The ornamental design for a golf club head, substantially as shown.
